UNITED STATES PATENT OFFICE.

RICHARD C. NEPTUNE, OF ST. LOUIS, MISSOURI.

ROOFING.

1,226,904.

Specification of Letters Patent. Patented May 22, 1917.

Application filed May 24, 1916. Serial No. 99,511.

To all whom it may concern:

Be it known that I, RICHARD C. NEPTUNE, a citizen of the United States, and a resident of the city of St. Louis and State of Missouri, have invented a new and useful Improvement in Roofing, of which the following is a specification.

This invention relates to plastic sheet roofing, such as is made up in roll form for covering the roofs and sides of buildings; but it may be applied embodied also into shingles, roof plates, and imitation tiles for special roofs.

The object of the invention is a plastic ready roofing which will have greater strength and durability than the tar paper and felt and asphalt roofing now used for building purposes. A further object of the invention is a plastic roofing which will stand distortion and changes in temperature without cracking, which will retain its plastic condition for a long period of time under all conditions of temperature and weather, and which will tend to close up around nails or other fastenings driven through it to maintain its continuity watertight.

The invention consists in a suitable metallic meshwork, such as wire fabric, expanded sheet metal lathing, and the like, which is embedded in a continuous sheet of suitable non-hardening plastic cement, to form a flexible, waterproof, ready roofing. Further objects and details of the invention appear below in connection with the description of the forms of roofing shown in the accompanying drawing, and what the invention consists in is more particularly defined in the appended claims.

Referring to the drawings,

Figure 1 is a plan view of a portion of a sheet of roofing embodying the invention, the plastic cement being partly broken away to disclose the metal meshwork embedded therein;

Fig. 2 is a cross-section of a similar form of roofing, the wires of the meshwork being of uniform size; and

Fig. 3 is a cross-section of a form of the invention wherein expanded sheet metal is embedded in the plastic cement.

The meshwork 11 shown in Fig. 1 consists of woven wire netting, some of the strands of wire being heavier than the others to stiffen the sheet. The cement 12 is applied

to the meshwork on both sides so as to embed the wires completely and protect them from the weather. Fig. 2 shows a cross-section of the roofing shown in Fig. 1 except that all the wires in the meshwork in Fig. 2 are shown the same in size. In the roofing shown in Fig. 3 the meshwork 15 is sheet metal slitted and expanded to form open-work, upon both sides of which a heavy coating of plastic cement 14 is applied to embed the metal.

The plastic cement body for embedding the meshwork is preferably composed of a mixture of Chinese wood oil and Kauri gum, elaterite, gilsonite, parolite or asphalt residue, or a mixture of several of said ingredients, brought to a paste consistency by the addition of asbestos fiber, asbestos, or similar fibrous substance. The proportion of liquid ingredients may be from thirty-five to sixty-five per cent. of the whole mixture, depending upon the kind of oil used and the consistency desired for spreading on the particular form of meshwork used. The proportions of the several oils used should be such as to make a smooth pasty mixture which spreads easily without sticking to the rolls or other spreading devices, and which dries out on the surface in the form of a tough, elastic film and which is plastic and retains its cohesiveness beneath the surface. The cement may be made substantially white in color, or suitable coloring matter may be added to bring it to any desired hue.

Roofing made as described above is sufficiently flexible to be shipped in rolls, and can be readily cut to suit the work in hand. It may also be made in plates or shingles and shipped in bundles. The surface is dry and hard, that is, it is neither oily nor sticky, and the color extends through the material and hence never fades nor wears off. The surface film is tough, and air and waterproof, thereby protecting the body of the material and the metal meshwork from oxidation. If the surface film becomes broken, the inner pasty material will immediately form another film surface and will maintain its continuity. The inner pasty material clings to nails or other fastenings driven through the roofing and prevents leaks at such places, thereby eliminating most roof trouble.

It is evident that any suitable form of meshwork may be used as a foundation for the cement body, even non-metallic fabrics,

such as burlap, without departing from the invention; and the invention is not restricted to the forms and dimensions of the materials shown in the drawings.

5 I claim the following as my invention:

1. As a new article of manufacture, roofing consisting of a meshwork foundation embedded in a plastic body comprising Chinese wood oil and fiber.

10 2. As a new article of manufacture, roofing consisting of a meshwork foundation embedded in a plastic body comprising Chinese wood oil, gum or oil residue, and fiber.

15 3. As a new article of manufacture, roofing consisting of a meshwork foundation embedded in a plastic body having a superficial tough waterproof and airproof film and a pasty interior comprising a mixture of oil and fiber.

20 4. A flexible sheet material consisting of

a waterproof body having hard, tough outer surfaces, formed from it by exposure to the air and meshwork embedded in said body, said body being plastic between said surfaces about said meshwork.

25 5. A waterproof sheet material consisting of a metallic meshwork embedded in a homogeneous plastic body having a hard, tough surface and a pasty interior.

6. As a new article of manufacture, sheet 30 roofing comprising a web of reinforcing material covered with a plastic material having a soft interior and a hard surface, said plastic material having the capacity for renewing its hard surface where abraded to 35 protect and maintain its soft interior.

Signed at St. Louis, Missouri, this 22nd day of May, 1916.

RICHARD C. NEPTUNE.
